UNITED STATES PATENT OFFICE

JOHN H. HOWARD, OF HUNTINGTON PARK, CALIFORNIA, ASSIGNOR TO GLOBE OIL
TOOLS CO., OF LOS NIETOS, CALIFORNIA, A CORPORATION OF CALIFORNIA

WELL DRILLING BIT

Application filed June 14, 1930. Serial No. 461,203.

This invention relates to a well tool and relates more particularly to a well drilling bit. It is a general object of the invention to provide a simple, practical, and effective 5 bit for use in the rotary method of well drilling.

An object of the invention is to provide a well bit embodying rotatable cutters formed and mounted so that they positively rotate 10 relative to the shank or body of the tool to be particularly effective in drilling the formation.

It is another object of the invention to provide a bit in which cutters are mounted on 15 the shank to rotate about axes inclined relative to the longitudinal axis of the shank and have cutting parts or blades formed to engage the walls of a well bore to destroy the formation and to cause positive rotation of 20 the cutters.

It is another object of the invention to provide a well bit of the character mentioned in 25 which the cutting parts or blades of the cutters are formed to engage the side wall of a well bore throughout substantial portions of their lengths so that they are effective in causing rotation of the cutters to insure the efficient operation of the tool and so that the 30 wear is evenly distributed along the cutting edges of the blades.

Another object of the invention is to provide a bit having cutters mounted to rotate on axes inclined relative to the longitudinal axis of the shank in which portions of, say 35 the lower portions of, the longitudinal or reaming cutting edges of the cutting blades are curved to compensate for the inclination of the cutters so that they engage the formation throughout substantial portions of their 40 lengths to evenly ream the walls of a well bore and to cause positive rotation of the cutters.

It is a further object of the invention to 45 provide a well drilling bit of the character mentioned above that is particularly effective in drilling a straight vertical hole or bore. The longitudinal or reaming cutting edges of 50 the cutter blades by engaging comparatively large portions of the side wall of a well bore guide the bit to drill a straight bore.

Other objects and features of the invention will be best and more fully understood from the following detailed description of a typical form and application of the invention, throughout which description reference is had 55 to the accompanying drawings, in which:

Fig. 1 is a view illustrating the bit provided by the present invention in operating position in a well bore. Fig. 2 is an enlarged side elevation of the bit illustrating it in operating 60 position in the well bore. Fig. 3 is a vertical detailed sectional view taken as indicated by line 3-3 on Fig. 2. Fig. 4 is an enlarged transverse detailed sectional view taken as indicated by line 4-4 on Fig. 3. Fig. 5 is a 65 diagrammatic view illustrating the cutters within the well bore, being a view taken at the upper ends of the cutters and looking down on the cutters. Fig. 6 is a diagrammatic view of the cutters in the well bore, being a 70 side elevation of the cutters, and Fig. 7 is a diagrammatic view illustrating the relative positions of the cutters and illustrating the manner of generating the reaming edges of 75 the blades.

The construction of the shank or body 10 may be varied somewhat, depending upon the number of cutters provided on the bit, the kind of formation in which the bit is to be operated, etc. In the particular form of the 80 invention illustrated in the drawings the body 10 is designed to carry two cutters 11 and includes a main shank portion 13 and two enlargements 14 for mounting or carrying the cutters 11. The shank portion 13 is prefera- 85 bly of round cross sectional configuration and is provided at its upper end with an upwardly projecting tapered screw-threaded pin 15. The pin 15 is provided to facilitate attachment of the bit to an operating string. In the 90 particular case illustrated in the drawings the pin 15 is threaded into a socket 16 in the lower end of a drill collar 17 carried at the lower end of an operating string 18.

The enlargements 14 project radially out- 95 ward at the lower end of the shank portion 13. In the case illustrated where two cutters 11 are mounted on the body the enlargements 14 project outwardly at diametrically opposite sides of the body. The enlargements 100

14 are inclined relative to a vertical plane passing through the longitudinal axis of the body 10. The enlargements 14 are oppositely disposed or oppositely inclined 5 and preferably have their outer or projecting sides rounded as shown in the drawings. The body 10 is recessed at the upper ends of the enlargements 14 to provide flat upper ends 19 on the enlargements. The 10 upper ends 19 of the enlargements 14 are normal to the angles of inclination of the enlargements. The lower ends of the enlargements 14 are preferably flat and are parallel to the upper ends 19 and at right angles to 15 the longitudinal axes of the enlargements. The body 10 is provided with a central longitudinal circulation passage 20. The passage 20 extends vertically through the body 10 from the upper end of the pin 15 to the lower 20 end of the body 10. The lower portion of the passage 20 is restricted or of reduced diameter so that fluid is discharged at high velocity from the lower end of the tool.

The cutters 11 are rotatably mounted at the 25 lower ends of the enlargements 14. The cutters 11 are mounted to rotate about axes parallel with the longitudinal axes of the enlargements 14. The axes R of rotation of the cutters 11 are oppositely inclined as will be readily apparent from an inspection of Fig. 7 of the drawings. The cutters 11 are rotatably mounted on straight shanks or stems 21 arranged through axial openings 22 in the enlargements 14. The openings 22 extend longitudinally through the enlargements 14 and the stems 21 are arranged in the openings 22 to project from the upper and lower ends of the enlargements. The portions 23 of the stems projecting from the lower ends of the 35 enlargements 14 rotatably carry the cutters 11 and are uniform in size and round in cross section. The openings 22 are tapered upwardly and inwardly and the stems 21 are shaped to conform to the openings 22. The fit 40 of the stems 21 in the openings 22 is such that the stems are prevented from moving upwardly in the openings. Nuts 24 may be screw-threaded on the projecting upper ends of the stems 21 to prevent downward displacement 45 of the stems. Locking keys or pins 25 may be provided to lock the nuts 24 in position.

The axes of the stems 21 are in planes angularly disposed relative to the longitudinal axis of the shank or body 10 so that the 50 cutters 11 rotatably mounted on the lower projecting portions 23 of the stems are rotatable about axes lying in parallel planes parallel to the axis of rotation of the body and the axes of rotation of the cutters are inclined upwardly and outwardly in opposite directions relative to a vertically disposed plane passing through the longitudinal axis of the body 10. The cutters or cutter bodies 11 are provided with openings or sockets 26 55 receiving the portions 23 of the stems. The

cutters 11 may be retained on the stems 21 in any suitable manner. In the particular case illustrated the cutters 11 are retained on the stems 21 by means of retaining members 25^a arranged in registering annular grooves 27 in the sockets 26 and the axial portions 23 of the stems 21. The members 25^a retain the cutters on the stems 21 so that they are free to rotate and are held against longitudinal displacement. Thrust washers 28 may be arranged on the stems 21 between the cutters 11 and the bottoms of the enlargements 14. In practice the thrusts, during operation, may be taken by the lower ends of the pins 21, and the washers 28 may receive the thrusts upon wearing of the cutters and pins. The stems 21 may be held against rotation in the openings 22 by keys 29.

The cutting parts or cutting blades 12 are provided on the cutters or cutter bodies 11 to remove the formation and are such that they cause rotation of the cutters 11 relative to the body 10 when the body is rotated. There is preferably a plurality of cutting blades 12 provided on each cutter, the number and spacing of the blades depending upon the kind of formation in which the tool is intended to operate. In the preferred form of the invention there are two series or groups of cutting blades provided on each cutter 11. The cutters 11 are preferably provided with a plurality of main cutting and reaming blades 30 for engaging the bottom and side walls of the well bore B, and reaming blades 31 for engaging the side walls of the bore B. The blades 30 and 31 project tangentially from the cutter bodies 11 and extend longitudinally or axially of the cutter bodies. In the particular form of the invention illustrated in the drawings, the blades 30 and 31 are substantially tangential to concentric circles having diameters approximately one fourth as great as the diameters of the cutter bodies.

The main cutting blades 30 are equally spaced about the central axes of the cutters and the reaming blades 31 may be arranged between the main blades 30. The main cutting blades 30 project outward from the cutter bodies 11 and extend longitudinally of the cutters from the upper ends of the cutters to points below the lower ends of the cutters. The blades 30 may be of substantially uniform thickness throughout their lengths. The main cutting blades 30 project downwardly from the cutter bodies 11 to engage the formation at the bottom of the well bore B and are provided with cutting edges 32 at their lower ends to remove the formation at the bottom of the bore. The cutting edges 32 are pitched to effectively shear the formation at the bottom of the well bore. The inner edges of the downwardly projecting portions of the cutting blades 30 may be curved upwardly and inwardly from the cutting edges 32 to the bottoms of the cutter bodies 11. The

cutting blades 30 are of the same size and are positioned and related so that the entire bottom of the well bore is engaged or acted upon by the cutting edges 32 during a complete revolution of the tool with the exception of a small central core which is destroyed by the fluid discharging through the passage 20. The lower cutting edges 32 of the blades may be comparatively straight and are inclined relative to the axes of rotation of the cutters to effectively act upon the bottom of the well bore.

The reaming or side cutting edges of the blades 30 and 31 are designed to act upon the side walls of the well bore B to cut the bore to full size and to positively cause rotation of the cutters to ensure the effective operation of the tool. The shape of the longitudinal or reaming edges of the cutting blades 30 and 31 is a feature of the invention and provides a particularly effective well drilling tool. In accordance with the preferred form of the invention, the lower portions 33^a of the longitudinal or reaming edges 33 of the blades 30 are curved and the curvature or shape of the lower edges 33^a is such that they actively engage the walls of the well bore throughout their lengths. Due to the inclination of the axes of rotation of the cutters from the vertical, the edges 33 successively engage the walls of the well bore. In accordance with the preferred form of the invention, the lower portions 33^a of the edges 33 of the blades are curved longitudinally about a point adjacent the intersection of planes including the axes of rotation of the cutters and the central axis of the well bore B. In other words, the general curvature of a cutting edge 33^a is determined by describing an arc in a horizontal plane about an axis adjacent the point of intersection of a plane including an axis R of a cutter 11 and the bore axis A and then projecting the arc downward along the lower portion of the blade 30 which is pitched at 15° from the vertical. It will be obvious that the inclination of the cutters from the vertical will determine the curvature of the cutting edges 33^a of the cutting blades.

In practice it has been found desirable to pitch the cutters 11 to rotate about axes approximately 15° from the vertical axis of the well bore B. Fig. 5 of the drawings is a diagrammatic view taken on a horizontal plane normal to the axis A of the well bore B intersecting the axes of rotation R of the cutters at the upper ends of the cutters. The circle B represents the walls of the well bore at the upper ends of the cutters where it is cut to full size. The curves X in Figs. 5 and 6 represent the paths of the upper ends of the cutting blades, relative to the body of the tool only, and the curves Y represent the paths of the lower edges of the blades 30 with respect to the shank or body of the tool, if designed to cut to the same diameter as the

upper ends. The paths of movement of the upper and lower edges of the blades during operation of the tool are approximately hypotrochoids.

In practice the lower edges are made to cut to a diameter slightly less than that cut by the upper ends, for instance, they are made to cut to a diameter represented by the circle B'. When formed in this manner the lower ends of the edges 33 describe the circles Y'. The upper portions of the longitudinal or reaming cutting edges 33 of the cutters may be straight and the lower portions 33^a extend gradually between the straight upper portions and the lower edges of the blades as shown in Figs. 5 and 6 and engage the walls of the well bore B throughout their lengths. The side edges 33 connect the curves X and Y' and the curved portions 33^a have centers adjacent the point D of intersection of the plane intersecting the axes of rotation R of the cutters at the upper ends of the cutters and the axes A of the well bore. In practice the centers of curvature of the cutting edges 33^a may be moved out from the point of intersection D toward the respective cutters 30 so that the curvatures of the edges 33^a will have shorter radii. For example, the centers of curvature of the cutting edges may be at the points D' so that the blades have cutting edges 33^a shown in broken lines connecting the circles X and Y'. By forming the cutting blades with edges 33 curved about points D' outwardly of the point of intersection D, the blades are particularly effective as the edges 33^a cut into the formation and effectively destroy the formation at the sides of the well bore B upon the rotation of the tool. Further, if desired, the angle W of inclination of the cutters from the vertical axis A of the well bore may be increased or decreased so that the point of intersection D of the horizontal plane passing through the points of intersection of the axes of the cutters and the upper ends of the cutters will be moved vertically along the axis A of the bore giving the cutters either a greater or smaller cutting diameter at their lower edges Y. It has been found practical, however, to pitch the cutters 11 at substantially 15° from the vertical and to curve the edges 33^a about points slightly outward of the point of intersection D, for example, about the points D' so that the lower ends of the edges 33 cut the bore to the line B'. By curving the edges 33^a in this manner, they act upon the walls of the well bore in an effective manner and positively cause rotation of the cutters 11.

The upper or reaming cutters 31 have cutting edges 34 of the same configuration as the upper portions of the edges 33 of the blades 30 to aid in reaming or destroying the formation at the upper portions of the blades 30. A blade 31 may be provided between each main blade 30 as illustrated in the drawings. The

reaming blades 31 may extend longitudinally of the cutter bodies between their upper and lower ends.

It is believed that the operation of the bit provided by the present invention will be readily apparent from the foregoing detailed description. The invention provides a bit wherein the cutting action of the cutting blades 30 and 31 is distributed throughout the lengths of the blades so that the wear on the blades is evenly distributed. By curving the lower portions 33* of the edges 33 of the cutting blades so that they engage the formation of the well bore throughout their lengths, the bit operates to cut the bore to size for a substantial period, as the blades will remain to size until worn throughout their length. The edges 33 being formed or shaped to effectively engage the side walls of the bore 20, cause the cutters 30 to be rotated so that they are effective in cutting the formation and so that the cutters will not track in the formation. Further, the edges 33 and 34, being shaped in the manner described, are particularly effective in guiding the bit to drill a straight vertical hole. The circulation fluid discharges from the passage 20 between the cutters 11 to destroy the small core left by the cutters and to flush the blades 30 and 31 of the cutters.

Having described only a typical preferred form of my invention, I do not wish to limit myself to the specific details set forth, but wish to reserve to myself any changes or variations that may appear to those skilled in the art or fall within the scope of the following claims:

Having described my invention, I claim:

1. A well bit including, a body to rotate about a vertical axis, a cutter mounted at the lower end of the body to rotate about an axis in a plane inclined downwardly and outwardly relative to the vertical axis of the body, and cutting parts on the cutter having cutting edges to engage the formation at the bottom of a well bore to make a substantially flat bottom wall in the bore, and having substantially parallel longitudinally curved side edges curved downwardly and inwardly with respect to the axis of rotation of the cutter to engage the formation at the side of the well bore through substantial portions of their lengths to form a round bore.

2. A well bit including, a body, a cutter mounted at the lower end of the body to rotate about an axis in a plane inclined relative to the vertical axis of the body, and a plurality of circumferentially spaced longitudinal cutting blades on the cutter having lower cutting edges to engage the formation at the bottom of a well bore to make a substantially flat bottom wall in the bore, and substantially parallel longitudinal side edges curved downwardly and inwardly with respect to the axis of rotation of the cutter to engage the side

wall of the well bore throughout substantial portions of their lengths to cut a round bore.

3. A well bit including, a body, a cutter mounted at the lower end of the body to rotate about an axis in a plane inclined relative to the vertical axis of the body, and a plurality of circumferentially spaced cutting blades on the cutter, the spacings of the several blades being substantially uniform throughout the lengths of the blades, the blades having lower cutting edges to engage the formation at the bottom of a well bore, to cut a substantially flat bottom wall in the bore, and longitudinally curved side edges curved downwardly and inwardly with respect to the axis of rotation of the cutter to engage the side wall of the well bore throughout their lengths to cut a round bore.

4. A well bit including, a body to rotate about a vertical axis, cutters mounted at the lower end of the body at opposite sides of the vertical axis of the body to rotate about axes in planes inclined relative to the vertical axis of the body and in opposed angularity relative to each other, and spaced cutting parts on the cutters, the spacings of the cutting parts being uniform throughout the lengths of the cutting parts, the cutting parts having lower cutting edges to engage the formation at the bottom of a well bore to cut a substantially flat horizontal bottom wall, and longitudinally curved side edges curved inwardly and downwardly relative to the axes of rotation of the cutters to engage the wall of the bore throughout substantial portions of their lengths to cut a round bore.

5. A well bit including, a body, cutters mounted at the lower end of the body at opposite sides of the vertical axis of the body to rotate about axes in planes inclined relative to the vertical axis of the body and in opposed angularity relative to each other, and cutting parts on the cutters having lower cutting edges to act on the formation at the bottom of a well bore, and side cutting edges extending longitudinally of the cutters and being longitudinally curved inwardly and downwardly relative to the axes of rotation of the cutters to act on the formation at the side wall of the bore to cut a round bore and cause rotation of the cutters, the cutters having diameters less than one half the diameter of the bore.

6. A well bit including, a body, cutters suspended at the lower end of the body at opposite sides of its axis to rotate about axes in planes inclined relative to the vertical axis of the body and in opposed angularity to each other, and spaced cutting blades on the cutters having lower cutting edges to act upon the formation at the bottom of a well bore to cut a substantially horizontal bottom wall, and longitudinal side cutting edges curved inwardly and downwardly from their upper ends to act upon the formation at the wall of the well bore, the spacing of the adjacent cut-

ting blades being uniform throughout the lengths of the blades.

7. A well bit including, a body, a cutter suspended at the lower end of the body to rotate about an axis in a plane inclined relative to the vertical axis of the body, and spaced cutting blades on the cutter having transverse lower cutting edges to act upon the formation at the bottom of a well bore, and 10 longitudinal side edges with substantially axial upper portions and lower portions curved about a point substantially coincident with the point of intersection of a plane including the axis of rotation of the cutter and 15 the axis of rotation of the body, the spacing of the adjacent cutting blades being uniform throughout the lengths of the blades.
8. A well bit including, a body, a cutter mounted at the lower end of the body to rotate 20 about an axis in a plane inclined relative to the axis of rotation of the body, and spaced longitudinal cutting parts on the cutter extending throughout the length of the cutter and having lower cutting edges to cut a substantially flat bore bottom and having side 25 cutting edges with their lower portions curved about a point adjacent the point of intersection of said plane and the axis of rotation of the body, the spacing of the cutting parts being substantially equal throughout the lengths of the cutting parts.

9. A well bit including, a body, a cutter mounted at the lower end of the body to rotate about an axis in a plane inclined relative 35 to the axis of rotation of the body, and circumferentially spaced longitudinal cutting parts on the cutter, the spacing of the cutting parts being uniform throughout the lengths of the cutting parts, the cutting parts having 40 side cutting edges curved longitudinally about a point adjacent the point of intersection of said plane and the axis of rotation of the body to engage the formation at the wall of a well bore for substantial portions of their 45 lengths to cut a round bore and having substantially transverse lower cutting edges to engage the formation at the bottom of the well bore to cut a substantially flat horizontal bottom wall.

- 50 10. A well bit including, a body, a cutter mounted at the lower end of the body to rotate about an axis in a plane inclined relative to the axis of rotation of the body, and circumferentially spaced longitudinal cutting 55 parts on the cutter having cutting edges curved about a point radially outward of the point of intersection of said plane and the axis of rotation of the body, the spacing of the cutting parts being substantially equal 60 throughout the lengths of the cutting parts.

11. A well tool for use on a drilling string including a body having a central longitudinal axis concentric with the axis of rotation of the drilling string, cutters mounted at the 65 lower end of the body at opposite sides of its

axis to rotate about axes in planes inclined relative to the longitudinal axis of the body and in opposed angularity relative to each other, and cutting parts on the cutters extending throughout the lengths of the cutters and 70 projecting from the lower ends of the cutters, and having cutting edges at their lower ends to cut a substantially flat horizontal bore bottom and having longitudinal cutting edges with portions curved downwardly and inwardly, the said portions of the cutting edges of the cutting parts of a cutter being curved about a point substantially coincident with the point of intersection of a plane including 75 the axis of rotation of the said cutter and the longitudinal axis of the body, the cutters having maximum diameters less than one-half the diameter of the well bore.

In witness that I claim the foregoing I have hereunto subscribed my name this 24th day 85 of May, 1930.

JOHN H. HOWARD.
